UNITED STATES PATENT OFFICE.

WALTER E. ZIEGNER, OF PHILADELPHIA, PENNSYLVANIA, ASSIGNOR TO AMERICAN MACHINERY CO., INC., OF PHILADELPHIA, PENNSYLVANIA, A CORPORATION OF DELAWARE.

FEEDING DEVICE.

Application filed August 26, 1922. Serial No. 584,532.

To all whom it may concern:

Be it known that I, WALTER E. ZIEGNER, a citizen of the United States, residing at Philadelphia, in the county of Philadelphia and State of Pennsylvania, have invented certain new and useful Improvements in Feeding Devices, of which the following is a specification.

The object of my invention is to provide 10 a novel, simple and efficient screw feeding device for feeding materials of various kinds in powdered and other form from hoppers or other containers.

The invention is particularly adapted for 15 use in connection with box or carton filling machines wherein the material to be introduced to the boxes or cartons is fed from a hopper through a discharge tube and permitted to drop by gravity from the tube or 20 forced therefrom and packed into the boxes or cartons by the pressure of the feeding device; and the invention aims to provide a device which will stop the feeding of the material immediately when the operation of 25 the feeding device is stopped and which will prevent the material from falling from within the discharge end portion of the tube between box or carton filling operations.

The invention consists in the novel construction, combination and arrangement of parts hereinafter described and claimed.

In the accompanying drawings illustrating my invention.

Figure 1 is a vertical section through a 35 hopper provided with a feeding device embodying my invention, showing material in the lower portion of the hopper to be fed therefrom.

Figure 2 is an enlarged view of the lower 40 portion of Fig. 1, omitting the material within the hopper.

Figure 3 is a section through the feeding tube, on line 3—3 of Fig. 2, to a slightly different position.

Figure 4 is a view of the bottom of the screw shown in Fig. 3.

Figure 5 is a view similar to Fig. 4, showing the plate on the bottom of the screw adjusted to a different position.

Figure 6 is a view similar to Fig. 3, showing a modification of the plate carried by the bottom of the screw.

Figure 7 is a view of the bottom of the screw shown in Fig. 6.

Referring to the drawings, 2 designates a

hopper which may be of any suitable shape and size for its intended purpose. The bottom of the hopper 2 is provided with a tube 4 which is suitably secured thereto and which extends downwardly therefrom. The 50 lower end of the tube 4 is open and the upper end thereof communicates with the hopper 2, and loose material 2^a in powdered or other form is adapted to be fed from the hopper through the tube 4 and discharged 55 from the bottom thereof for filling boxes or for other purposes.

Extending through the tube 4 from the bottom thereof to and above the top thereof and into the hopper 2 is a screw 5 carried 70 by the lower end of a vertical shaft 6 turning in a tubular shaft 7 which is mounted to turn in a bearing 8 which extends down into the hopper 2 and is supported by a plate 9 formed thereon and secured upon a bracket 75 10 on the top of the hopper. The upper end portion of the shaft 6 extends above the top of the tubular shaft 7 and has a bevel gear wheel 11 secured thereon through which the shaft 6 may be driven from any suitable 80 source of power. The hub of the gear wheel 11 carries a pinion 12 in mesh with a gear wheel 13 which turns on a shaft 14 supported by and extending upwardly from a block 15 secured upon the plate 9; and the hub of the gear wheel 13 carries a pinion 16 in mesh with a gear wheel 17 secured to the upper 85 end of the tubular shaft 7, whereby, when the shaft 6 is turned to actuate the screw 5 to feed material through and from the tube 90 4, the tubular shaft 7 will be turned at a slower speed. The tubular shaft 7 carries suitably shaped stirring or agitating arms 18 and 19 for stirring or agitating the material within the hopper 2 and causing it to 95 feed downwardly therein to the sphere of influence of the feed screw 5.

That portion of the screw 5 which extends above the top of the tube 4 and into the hopper 2 gradually increases in diameter, from 100 the top of the tube 4 to the top of the screw, as clearly illustrated, to exert a greater feeding action upon the material 2^a in that portion of the hopper 2 which is immediately above the top of the tube 4 and which is of 105 greater cross sectional area than that of the tube.

The lower end portion of the screw 5, for a short distance above the bottom thereof, is of less pitch than that of the remaining 110

portion of the screw which extends through the tube 4 to restrict or reduce the area of the lower end portion of the spiral-like passage 20 formed by and between the screw 5 and tube 4, for a purpose presently explained.

Fitted against the bottom of the feed screw 5 and extending at right angles to the axis thereof is a horizontal plate 21 which 10 is adjustable circularly about the axis of the screw 5 and which is held in its different positions of adjustment by a central clamping screw 22 extending through an opening in the plate 21 and screwed into the feed screw 5, as illustrated. The plate 21 is rotatable by and with the screw 5 within the extreme lower end portion of the tube. The plate 21 shown in Figs. 1 to 5, inclusive, has a plurality of radial arms 23 which partially 20 block the lower end of the spiral-like passage 20; and the plate 21, shown in Figs. 6 and 7, is shaped, as illustrated, to partially block the passage 20.

That portion of one of the arms 23 shown 25 in Fig. 4, and that portion of the plate 21, shown in Fig. 7 which extends between the terminal edge 24 of the feed screw blade or thread and the edge 25 of the plate 21, forms, in effect, a continuation of the feed 30 screw blade or thread, therefore it will be understood that by adjusting the plate 21 to bring the edge 25 thereof farther from or nearer to the edge 24 of the feed screw 5 the extent of the restriction of the lower end 35 portion of the passage 20 may be increased or decreased as required to meet varying conditions or properly to feed materials of various kinds.

The arms 23 shown in Fig. 4, not only 40 serve to partially block the lower end of the passage 20, but they also serve as breakers to break up the material fed by the screw 5 through and from the tube 4 when the screw is in operation.

45 I have discovered that by restricting and partially blocking the lower end of the passage 20 by the plate 21 and the reduced pitch of the lower end portion of the feed screw 5 I am enabled, by the operation of the feed screw 5, to pack the material in the lower or delivery end portion of the tube 4 to a greater extent than it is packed in the upper portion of the tube by the action of the screw, and that, as a result thereof, the 50 feeding of the material from the bottom of the tube 4 stops substantially immediately upon the cessation of the operation of the screw, and that after the feed screw has been stopped extremely little or no material 55 will fall from the bottom of the tube. The importance of this, when the invention is used in connection with weighing or measuring machines, will readily be appreciated.

60 The shape of the plate 21 and the number of arms 23 may be changed or modified

to suit the requirements of the particular material being fed through and from the tube 4.

I claim as my invention:—

65 1. In a feeding device, the combination of a tube, and a screw mounted to turn therein to feed material therethrough and discharge it therefrom, said screw and said tube forming a spiral-like passage, said screw having means at the lower end thereof to restrict the discharge end of the passage.

70 2. In a feeding device, the combination of a tube, a screw mounted to turn therein to feed material therethrough and discharge it therefrom, said screw and said tube forming a spiral-like passage, a plate at the discharge end of the screw restricting the discharge end of the passage, and means to secure the plate to the screw in different positions of adjustment varying the extent of the restriction.

75 3. In a feeding device, the combination of a tube, a screw mounted to turn therein to feed material therethrough and discharge it therefrom, said screw and said tube forming a spiral-like passage, a plate set substantially at right angles to the axis of the screw at the discharge end thereof and being adjustable circularly about said axis, said plate partially blocking the discharge end of said passage, and means to secure the plate to the screw in different positions of adjustment.

80 4. In a feeding device, the combination of a tube, a screw mounted to turn therein to feed material therethrough and discharge it therefrom, said screw and said tube forming a spiral-like passage, a plate set substantially at right angles to the axis of the screw at the discharge end thereof and being adjustable circularly about said axis, 85 said plate having a plurality of radial arms 90 partially blocking the discharge end of said passage, and means to secure the plate to the screw in different positions of adjustment.

95 100 4. In a feeding device, the combination of a tube, a screw mounted to turn therein to feed material therethrough and discharge it therefrom, said screw and said tube forming a spiral-like passage, a plate set substantially at right angles to the axis of the screw at the discharge end thereof and being adjustable circularly about said axis, 105 said plate having a plurality of radial arms 110 partially blocking the discharge end of said passage, and means to secure the plate to the screw in different positions of adjustment.

115 5. In a feeding device, the combination of a hopper having a discharging tube of less cross sectional area than that of the hopper, and a screw extending into the tube and into a portion of the hopper and mounted to turn therein to feed material from the hopper into and through the tube and discharge it from the latter, that portion of the screw 120 which extends into the hopper being of larger diameter than that portion thereof which extends into the tube and being spaced from the surrounding wall of the hopper.

125 6. In a feeding device, the combination of a hopper having a discharging tube of less cross sectional area than that of the hopper, and a screw extending into the tube and into a portion of the hopper and 130

mounted to turn therein to feed material therein to feed material therethrough and 10
from the hopper into and through the tube
and discharge it from the latter, that portion
of the screw extending away from the
5 tube and into the hopper being of gradually
increasing diameter and being spaced from the surrounding wall of the hopper.

7. In a feeding device, the combination
of a tube, and a screw mounted to turn

therein to feed material therethrough and 10
discharge it therefrom, the pitch of the upper
portion of the screw being constant and
the pitch of the screw at the discharge end
portion thereof being less than that of the
said upper portion thereof within the tube. 15

In testimony whereof I affix my signature hereto.

WALTER E. ZIEGNER.
